7 Claims. (Cl. 112—215)

This invention relates to feeding devices for sewing machines and the like.

It is the primary object of the present invention to provide an improved form and construction of feeding device which is applicable in particular to the feeding of fibrous materials in a loose, flocculent layer to the needle or needles of a sewing machine, which latter is adapted to form one or more rows of reinforcing stitching in the layer of fibrous material. The invention is especially useful where the fibrous layer is entirely unsupported except for the stitching, although the invention is also applicable to cases where a backing of textile or other fabric, paper, or the like is used to support the fibrous layer, or where the latter is sandwiched between a pair of such supporting sheets to form quilting.

According to the invention there is provided for feeding loose fibrous material to a sewing or like machine, a feeding device comprising a reciprocating presser foot which is driven by a pair of cranks or equivalent, said foot having a rigidly mounted part engaging with one of the cranks or equivalent and being connected with the other crank or equivalent by means of a pivotally mounted link member.

As a further aspect of the invention the feeding device may comprise a presser foot which is driven by a pair of cranks or equivalent, one being arranged to act upon the presser foot at that end adjacent the sewing machine needle, and the other being displaced therefrom towards the entry end of the presser foot.

Conveniently the cranks or equivalent have unequal radii of action, that crank or equivalent disposed nearer the entry end of the presser foot preferably having the larger radius of action; also the cranks or equivalent may be displaced in place relative to one another, that crank or equivalent corresponding to the entry end of the presser foot usually being retarded with respect to the crank or equivalent adjacent the sewing machine needle or needles. If desired the cranks or equivalent may be provided upon mutually parallel shafts which are driven in common. Further the presser foot may comprise a plate which, at a position adjacent the sewing machine needle, is provided with a rigidly carried upwardly extending bracket, the upper end of which engages with one of the cranks or equivalent; one end of the presser foot may be formed with a plurality of forwardly directed fingers arranged to press upon the fibrous material alongside the needle or needles of the sewing machine.

The invention is illustrated by way of exam-

ple in the accompanying diagrammatic drawing, in which:

Figure 1 is a side elevation of one form of feeding device, the associated needlebar and the driving mechanism being shown in broken lines;

Figure 2 is a sectional plan taken on the line 2—2 of Figure 1; and

Figures 3a to 3h inclusive are side elevations showing the various stages in the cycle of operations of the feeding device shown in Figures 1 and 2.

The feeding device shown in Figures 1 and 2 comprises a substantially rectangular plate 10, which is curved longitudinally so that its under surface 11 is convex. The forward end of the plate 10, i. e., that end which lies adjacent the sewing machine needles 12, is formed with a plurality of forwardly extending projections 13 adapted to extend alongside and between the needles 12 so as to support the fibrous material while the latter is being sewn. The fibrous material is indicated in broken lines at 14, and is conveniently delivered to the entry end 15 of the feeding device by means of an endless band conveyor 16 which passes over a roller 17, the fibrous material 14 being thus transferred to the surface of the throat plate 18 of the sewing machine.

In the sewing machine which is shown in the drawing the needles 12 which are associated with the plate 10 are carried by a needle-holder 19 at the lower end of a single needlebar 20, the latter being driven by means of an eccentric 21 upon a driving shaft 22 and being arranged to slide within a pivoted guide member 23 in the known manner.

For imparting the desired motion to the plate 10 a pair of transverse shafts 24 and 25 having crank pins 26 and 27 respectively are driven each in an anti-clockwise direction at a speed equal to that of the driving shaft 22 for the needlebar 20, this effect conveniently being obtained by arranging for a driving chain 28 to pass around sprockets 29 and 30 upon the shafts 24 and 25, and around a driving sprocket 31 driven from the shaft 22, but in the opposite direction, by means of a pair of equal-diameter gear wheels 32 and 33. The crank pin 26 fits rotatably within a bearing at the upper end of a bracket 34 secured rigidly to the forward part of the plate 10, while the latter is formed adjacent its entry end 15 by a pair of upstanding lugs 35 carrying a transverse pin 36, which forms the lower pivotal mounting of a link 37, the upper end of said link being fitted to the crank pin 27.

The radius of action of the crank pin 27 is preferably somewhat greater than that of the crank pin 26, and if the crank pin 26 is arranged to lead slightly, say by 45°, the movements of the plate 10 constituting the presser foot will be substantially as shown in Figure 3. As the crank pin 27 reaches its top dead centre, as shown in Figure 3a, the plate 10 assumes its substantially fully-raised position, with its entry end 15 well raised to receive the relatively loose incoming layer of fibrous material. The plate 10 then moves downwards bodily with the requisite forward motion, as shown in Figures 3b to 3e inclusive, the entry end 15 of the plate 10 having a greater downward movement than the forward end thereof. This forward end of the plate 10 then commences to rise slightly, as shown in Figure 3f, thus easing the pressure on the fibrous material adjacent the needles in readiness for the retracting movement of the plate 10, which is shown in Figures 3g and 3h.

The actual form and extent of the movement which is imparted to the plate 10 can be varied considerably by modifying the radii of action of the crank pin 26 and 27, the sense and magnitude of their relative phase displacement, the positions of the shafts 24 and 25 with respect to one another and to the plate 10, and the position of the pivot pin 36 with respect to the plate 10.

The invention is intended primarily for use in connection with sewing machines having a row of needlebars, each of which carries a plurality of needles so as to produce a large number of rows of stitching simultaneously. As it is usual for the needlebars of such machines to be run at different phases it will of course be realised that the corresponding presser foot will normally be timed to suit the needlebar to which it belongs. The shafts 24 and 25 could, however, extend completely across the machine so as to drive all of the presser feet, the crank pins 26 and 27 in each case being arranged to match the phase relationship of the eccentric 21 or equivalent driving mechanism of the corresponding needlebar 20. The under surface 11 of the plate 10 can, of course, be grooved longitudinally and/or transversely, or may be of any suitable shape or texture, so as to provide the desired gripping action in conjunction with the fibrous material to be sewn.

It will, of course, be understood that the arrangement which is illustrated is given merely as an example and that the construction of the feeding device can be modified in various ways to suit particular requirements.

What we claim is:

1. Means for feeding loose fibrous material to a sewing machine, including a plate extending in advance of the sewing machine needle and

5 forming a pressure foot to overlie and cooperate throughout its length with the material, a crank and link device connected with that part of the plate remote from the needle for alternately raising and lowering said remote part of the plate, and a continuously rotating crank device driven in common with the crank and link device and connected rigidly with that part of the plate adjacent the needle so that said adjacent part of the plate executes an up and down movement and simultaneously moves towards and away from the needle.

2. Means for feeding loose fibrous material along the throat plate and past the vertical reciprocating needle of a sewing machine; comprising an elongated combined presser and feed plate disposed above the throat plate and having its advance end adjacent the needle, a crank operating mechanism including an element rigidly connected with the plate adjacent its advance end, and a second crank operating mechanism including an element pivotally connected with the plate, remote from the rigid connection of said first element.

25 3. A construction as defined in claim 2, wherein in each crank-operating mechanism includes a crank, and wherein such cranks are of unequal radii of action respectively.

4. A construction as defined in claim 2, wherein 30 in each crank-operating mechanism includes a crank, and wherein the movement of one crank is retarded with respect to the movement of the other crank.

5. A construction as defined in claim 2, wherein 35 in each crank-operating mechanism includes a crank, and wherein the movement of the crank of the mechanism adjacent the advance end of the plate is accelerated with respect to the movement of the crank of the other crank mechanism.

40 6. Means for feeding loose fibrous or like material to a sewing or like machine, including a plate positioned above a throat plate of the machine and having advance and rear ends with 45 relation to the direction of feed of the material, means for operating the advance end of the plate, independent means for operating the rear end of the plate, and means to coordinate the respective operating means of the respective 50 ends of the plate to compel relatively different movements thereof, with respect to the material.

7. A construction as defined in claim 2 where- 55 in the element of the crank mechanism pivotally connected with the plate remote from the rigid connection of the first element, has a relatively larger radius of action than the element of the crank mechanism at the advance end of the plate.
